LEOPOLD POLLOCK, OF NEW ROCHELLE, NEW YORK, ASSIGNOR TO SHELDON POLLOCK,
OF YONKERS, NEW YORK

CHECK PROTECTING DEVICE

Application filed February 11, 1929. Serial No. 339,063.

This invention relates to check protecting devices. It is particularly directed to a device for mutilating portions of written papers to prevent forging alteration thereof.

An object of the invention is to provide a protective device of the character described which shall be compactly incorporated into a fountain pen, pencil or the like article so that the same may be conveniently carried on the person and ready for use when signing checks and the like papers.

A further object of this invention is to provide a device of the character described which shall be neat and compact in construction, relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention.

Fig. 1 is a perspective view of a fountain pen cap embodying the invention shown in position for mutilating a portion of a check;

Fig. 2 is a cross-sectional view taken on line 2—2 of Fig. 1;

Fig. 3 is a cross-sectional view taken on line 3—3 of Fig. 2;

Fig. 4 is a cross-sectional view taken on line 4—4 of Fig. 2; and

Fig. 5 is a side view of a fountain pen embodying the invention showing the cap in position when using the pen for writing.

Referring in detail to the drawings, 10 designates a fountain pen comprising the barrel 11 and cap 12.

The barrel 11 is of usual construction, being provided with a pen point 14, a threaded portion 15 and a closed end portion 16.

The cap 12 is tubular in shape and comprises a cylindrical portion 18 and an end wall 19. Adjacent the open end 20 thereof,

said tubular member is provided with an internal threaded portion 21 adapted to cooperate with threads 15 of the barrel portion 11 for attaching the cover to close the fountain pen in the usual manner. Said open end portion 20 is adapted for frictionally receiving the rear end portion 16 of the body in the usual manner for attaching the cover to the rear of the pen as shown in Fig. 5.

Incorporated into the cap portion 12 is the means for mutilating portions of a written paper such as a check and the like, for preventing alteration of the writing. The cap 12 is provided with a narrow diametric slot 22 in the end wall 19 thereof, and with aligned, longitudinal slots 23, 24 extending from the ends of slot 22. The cap 12 is thus partially split for receiving the edge portion 25 of a check 26 or any other paper, in a manner illustrated in Figs. 1 and 2. The cylindrical wall 18 of cap 12 is further provided with diametrically disposed slots 27, 28 preferably in a plane at right angles to the plane of the slots 22, 23, 24, and of somewhat greater width than the latter. Said slots 27, 28 terminate short of the ends of the cylindrical wall 18. Extending inwardly from said cylindrical wall 18 at points adjacent the outer ends 27a, 28a of said slots 27, 28 are aligned lugs 29, 30, parallelly disposed with respect to end wall 19 of the cover. Said lugs 29, 30 may preferably be formed integrally with said cylindrical wall 18 as by stamping said lugs from the wall portion in forming the slots 27, 28 and bending the stamped portions inwardly toward each other. Each of said lugs may be formed with a small bearing opening 31. Aligned with said openings 31 are similar bearing openings 32 formed in end wall 19 on each side of the slot 22.

Mounted within the tubular cap 12 on both sides of the split portion thereof and between lugs 29, 30 and end wall 19 are small cylindrical die members 33 provided with axial extensions 34, journaled in their respective pair of aligned openings 31, 32. The outer surfaces 35 of said cylinders 34 are preferably knurled, serrated or ridged in any suitable manner and are of such size that

adjacent portions of said surfaces are substantially in contact with each other.

It will now be clear that a sheet of paper such as a check having written portions thereon, may be inserted into the slots 22, 23, 24 of the cap 12. Upon application of the slight pressure on the cover at the split portion, the knurled cylinders press against the opposite portions of the check. Movement of the cover member with respect to the check will then mutilate the portion thereof over which the cylinders roll.

For guiding the cylinders over desired portions of the check, member 40 is slidably mounted on the cap 12. Said member 40 comprises a circular disc portion 41 loosely fitted within the cylindrical portion 18. Integrally formed with said disc is an extension 42 passing thru slot 28 and terminating in an enlarged finger piece 43, having a curved, knurled outer surface 44. Said piece 43 preferably extends beyond the sides of said slot 28 as at 43a thus providing guiding means for said stop member. Integrally formed with said disc 41 diametrically opposite to extension 42, is an extension 45 passing thru slot 29 and terminating in a spring clip member 46 pressing against the outer surface of the cap member for retaining the stop member in any adjusted position to which it may be moved.

In using the device 10 for indenting or mutilating checks, the stop member may be moved, by pushing the finger piece 43, to any desired adjusted position. The check may then be passed thru the split 22, 23, 24 to bring the edge 25 of said check into contact with the outer surface 51 of the disc 41. Movement of the cover with respect to the check may thereafter be affected for mutilating the writing on a straight line. To mutilate writing further from or closer to said edge 25, the stop member need merely be pushed to the proper position and the device actuated in similar manner.

If desired, when the cap 12 is not in use for indenting checks and the like, a thimble 13 may be frictionally fitted over the end of said cap to cover the split portion.

It will now be seen that a handy, convenient, check protector is provided which is constantly available for use, since it is carried with and forms part of the fountain pen. In this connection, it will be noted also that the invention may be embodied in practical form either by manufacturing the fountain pen cap portion with the check protecting device as a separate unitary article, the cap being dimensioned and otherwise constructed to correspond in size and shape to the standard fountain pens on the market, or by manufacturing fountain pens or the like articles complete with the specially constructed cap. In the former event, the cap made in accordance with the invention will replace in the

hands of the user the cap of the standard fountain pen owned by him.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described my invention I claim as new and desire to secure by Letters Patent:

1. In a device of the character described, a tubular member closed at one end and open at the other end, said closed end of said member being split for receiving a sheet of paper, means mounted within said member for mutilating a portion of said sheet, a cap member removably attached to said tubular member at said closed end, and an adjustable stop member slidably mounted within said tubular member adapted to contact the edge of said sheet.

2. In a device of the character described, a tubular member, one end of said member being split for receiving a sheet of paper, means mounted within said member for mutilating a portion of said sheet, an adjustable stop member associated with said tube adapted to contact the edge of said sheet, and a spring clip member attached to said stop member adapted to press against the outer surface of said tubular member for retaining said stop member against movement.

3. In a device of the character described, a tubular member, means for perforating paper mounted in said tube, said tube being provided with a longitudinal slot, and an abutment member slidably mounted in said slot, said member having a portion extending within said tube and a portion extending outside of said tube and adapted to press against the outer surface of said tube.

4. In a device of the character described, a tubular member provided with a longitudinal slot, an annular disc slidably within said tube, a spring clip on the outer side of said tube adapted to retain said disc against sliding movement and a portion interconnecting said clip and disc, extending thru said slot.

In testimony whereof I affix my signature.

LEOPOLD POLLOCK.
